Inventor:

M. Terhune

United States Patent Office.

M. TERHUNE, OF CHICAGO, ILLINOIS, ASSIGNOR TO HIMSELF AND WILLIAM H. CORE, OF NEW YORK CITY.

Design No. 3,475, dated May 4, 1869.

DESIGN FOR A SHOW-CASE.

The Schedule referred to in these Letters Patent and making part of the same.

To all whom it may concern:

Be it known that I, M. TERHUNE, of Chicago, Cook county, and State of Illinois, have invented a new and original Design for Show-Case; and I do hereby declare that the following is a full, clear, and exact description thereof, which will enable others skilled in the art to make and use the same, reference being had to the accompanying drawing, forming part of this specification.

The drawing represents a vertical transverse section of my new show-case.

This invention relates to a new show-case, which is of pentagonal cross-section, whereby a new effect is produced.

The front, or face A, of the case does not, as usually, extend up to the top plate B, but is connected with the same by an inclined plate, C, as shown, all these plates, A, B, and C, being of glass, secured in a suitable frame, D.

The bottom plate E, and the back F of the case, are made of wood, or other suitable material, of the ordinary form.

The peculiarity of this show-case consists in its having two rows of horizontal mouldings, D, and three separate rows of glass, while the ordinary show-cases have but one row of mouldings, and two rows, or plates of glass, one in front and one on top.

Having thus described my invention,

What I claim as new, and desire to secure by Letters Patent, is—

The design for show-cases, herein described.

The above specification of my invention signed by me, this 14th day of April, 1869.

M. TERHUNE.
